(57) **CLAIM**

The ornamental design for a welding table, as shown and described.

DESCRIPTION

FIG. 1 is a downward front perspective view of the design for a welding table;

FIG. 2 is an upward front perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof;

FIG. 8 is a bottom plan view thereof; and,

FIG. 9 is a downward front perspective view thereof with table legs extending from the welding table.

The broken lines in the drawings illustrate environmental structure and portions of the welding table that form no part of the claimed ornamental design.
